(57) CLAIM

The ornamental design for a view-box container, as shown and described.

DESCRIPTION

FIG. 1 is a perspective view of a view-box container according to our new design;

FIG. 2 is a front elevational view thereof;

FIG. 3 is a back elevational view thereof;

FIG. 4 is a top plan view thereof;

FIG. 5 is a bottom plan view thereof; and,

FIG. 6 is a right side elevational view thereof, the left side being a mirror image.

The bottles shown in broken lines in FIG. 1 are for illustrative purposes only and form no part of the claimed design.
